(57) CLAIM

The ornamental design for a shoe as shown and described.

DESCRIPTION

FIG. 1 is a front perspective view of a shoe showing my new design;

FIG. 2 is a side view thereof; and,

FIG. 3 is a rear perspective view thereof.

The broken line showing of the circular region represents an eyelet that forms no part of the claimed design. The broken line immediately adjacent to the interior of the shaded area defines a boundary of the claimed design and forms no part thereof. The unshaded areas form no part of the claimed design. The broken lines depicting the remainder of the shoe form no part of the claimed design.
